CLAMP FOR MASTER SHEETS OF PRINTING MACHINES

Lawrence H. Morse, Mentor, Ohio, assignor to Addressograph-Multigraph Corporation, Cleveland, Ohio, a corporation of Delaware

Application October 2, 1943, Serial No. 504,656

10 Claims. (Cl. 101—415.1)

1

This invention relates to a means for clamping one or more master sheets on a drum of a printing machine. One of the objects of the invention is to provide clamping mechanism which may take a variety of master sheets, whether the same be metal or paper or other material, and whether they are provided with a row of openings across one end (as is frequently the case) or have the end portion imperforate. My system provides such universal arrangement, both for the leading end of the sheet and the trailing end thereof, so that various forms of master sheets may be effectively clamped on the drum.

In carrying out my invention, I provide a clamp which may readily coact with the drum to clamp the end of a sheet between them and I also provide a supplemental clamp coacting with the first clamp to clamp a sheet between the two clamps, whereby the first mentioned clamp serves the double function of clamping either with the drum or with the second clamp, according to the nature of the sheet to be clamped.

Another feature of my invention relates to means for clamping the trailing end of a comparatively short master sheet which is not long enough to reach the normal trailing clamp. To effect this I provide two swinging hooks which may be idle within the drum or project beyond the same to pass through openings in such short master sheet adjacent the trailing end thereof to clamp the same. This feature allows the employment of a composite master composed of one sheet clamped by the normal clamp and a second sheet surmounting a portion of the first sheet and secured in part by one of the normal clamps and in part by my supplemental clamp.

The features above outlined, and others contributing to the operation and efficiency of my clamping system, will be more apparent from the following detailed description of a preferred embodiment illustrated in the drawings.

In the drawings, Fig. 1 is a plan of a drum equipped with my novel master sheet clamp; Fig. 2 is an enlarged cross section of the same in an offset plane indicated by the line 2—2 on Fig. 1; Fig. 3 and Fig. 4 are fragmentary cross sections on the correspondingly numbered lines on Fig. 1, illustrating respectively different positions of the clamping apparatus; Fig. 5 is a fragmentary plan of the same scale as Figs. 2, 3 and 4, illustrating the clamping device adjacent one end thereof; Figs. 6 and 7 are cross sections of the drum in an offset plane indicated by the line 6—6 on Fig. 1, illustrating respectively different positions of the parts shown; Fig. 8 is a diagrammatic illustra-

2

tion of the manner in which one printing sheet may be superposed on another.

In Figs. 1 to 7, 10 designates a suitable rotary drum having a segmental recess or gap 11 through its periphery. Adjacent one edge of the gap is a ledge adapted to form an anvil for the clamp to secure the leading edge of the sheet. As shown in the drawings, this ledge is provided by a flat bar 15 secured in the radial position to the drum 10 and having an outwardly facing longitudinal recess 16.

The clamping member for the leading end of the master sheet comprises a member 20 having a cross bar 21 longitudinal of the drum and a pair of end arms 22 pivoted on a shaft 23 mounted in the drum. The end members 22 and the bracing longitudinal bar portion 21 carry a longitudinal strip 24 which is bent on itself to provide an inwardly extending flange 25 in position 20 to coact with the groove 16. Two or more pins 26 (Fig. 4) carried by the bar 15 form suitable stops for the inner end of the sheet to be clamped on the drum. Springs 27 secured to the drum and to the arms 22 tend to maintain the flange 25 in coaction with the ledge 15 to deflect a very flexible sheet between them and effectively clamp it, as illustrated by the sheet designated A in Fig. 4.

I also secure to the cross bar 21 of this clamping yoke a face bar 28 having projecting pins or hooks 29 adapted to extend through openings in a master sheet.

The construction just described enables the mounting of the leading end of master sheets of various forms. If the sheet has a row of holes through it adjacent the end it may readily be hooked over the hooks 29. If the end portion of the sheet is imperforate, as is frequently the case with a paper sheet, it may be readily clamped by the flanged edge 25 which kinks the end portion of a sheet into the groove 16 as shown in Fig. 4.

To provide ready means to force the clamping member 22 backwardly away from the ledge 15, I mount in such clamping member a threaded sleeve 30 which carries a freely slidable rod 31 abutting the ledge 15. In a bifurcated head 32 on the sleeve I mount a cam arm 34. When the clamping means provided by the flange 25 and the ledge 15 is to be idle, the clamping arm 34 is positioned outwardly in alignment with the rod 31, as shown in Fig. 3. This draws the clamping member 20 outwardly so that the flange 25 is well away from the ledge 15 as shown in Fig. 3.

55 I will now describe the clamp or clamps for

the trailing edge of the master sheet or sheets. As shown in various views I have mounted at the other edge of the gap in the drum a stationary clamping ledge 40 provided by a strip of material doubled on itself at an acute angle. One arm of this member extends radially and is secured by screws or otherwise to the radial face of the drum at the gap, while the other arm 41 extends as a chord in a direction across the gap of the drum. In this chordal face I make a series of openings corresponding in position to openings in the master sheet to be clamped and I provide a clamping member having inwardly projecting teeth to occupy such openings.

The clamping member above mentioned comprises a pair of end arms 50 and a cross plate 51 having a reinforcing bar along its free edge portion, which bar has hooked teeth 53 adapted to extend through the openings in the face 41 of the anvil ledge. The arms 50 are provided with slots 55 which embrace the pins 54 projecting longitudinally inward from the end members of the drum, so that this clamping member is mounted both pivotally and slidably. A suitable spring tends to maintain the clamping member in its active or engaged position, and applies tension to the sheet in the act of clamping it.

I have shown for the above purpose a tension spring 56 anchored at one end to the clamping member and at the other end to a collar 58 which for convenience is mounted on the shaft 23 herefore mentioned. The direction of pull of the spring 56 is such that it tends to maintain the clamp edge 52 in coaction with the anvil flange 41 and at the same time tends to pull such edge in a chordal direction inwardly of the drum. Accordingly, when a sheet is anchored at its leading end by one or the other of the means herefore described, the clamp 50 may be rocked outwardly to the position shown in Fig. 6, and the perforated trailing end of the sheet projected over the ledge 41. Thereupon the release of the clamp 50 will permit the springs 56 to return it to the position shown in Fig. 7. In moving to such position the clamp teeth 53 will readily pass through the openings in the sheet, and, due to the sliding movement of the clamp on its pivot pins, the springs will cause the clamp to tension the sheet about the periphery of the drum.

I use the cross plate 51 of the main clamp described as an anvil for a supplemental clamp to engage a sheet which does not have the perforations for the teeth 53. As shown in several views suitable ears 59 of the main clamp 50 carry a cross rod 60. On this cross rod are pivotally mounted the flanged ends 61 of a cross plate 62 which lies over the plate 51 and is adapted to coact with it. A spring 65 coiled around the rod 60 and anchored at one end to one of the ears 59 and at the other end bearing against the plate 62 tends to maintain the plate 62 in engagement with the plate 51. The innermost edge of the plate 62 is curled outwardly and backwardly over the rod 60 to provide a finger grip 67.

The spring 65 is materially lighter in its action than the spring 56 so that if the operator's finger is applied to the ledge 67 as indicated in Fig. 3, the plate 62 may be swung away from the anvil plate 51 to provide an opening for the insertion of an imperforate plate. Then when the finger pressure is removed the spring 65 will return the surmounting plate into the position shown in Fig. 4 to clamp the sheet, indicated at A, between them. I prefer to make recesses 57 and complementary projections 69 on the two plates 51 and

62 to indent or perforate the end portion of a normally imperforate paper plate which may be clamped between the members thus insuring a tight engagement.

To prevent any looseness or indefiniteness in the action I prefer to lock the main clamp to the drum when the supplemental clamp is to be actuated, and conversely to lock the two clamps together when the main clamp is to be actuated, such locking together allowing the finger ledge 67 to operate the main clamp. This will now be described.

Mounted on the plate 51 of the main clamp are a pair of latch arms 70 each pivoted at 71 and normally held in either extreme position by a leaf spring 72 engaging either of two flat faces at an angle to each other on the arm back of the pivot. Each arm in one extreme position, as shown in Fig. 1, may lie beneath the inwardly projecting end of the corresponding pin 54 which form the pivotal mounting for the clamp. Such position causes an upright shoulder 73 on the latch lever to stand in front of the pin 54 thereby maintaining the clamp 51 in closed position while leaving the supplemental clamp free. With the latches 70 in this position as shown in Fig. 1, the main clamp is idle and the finger pressure on the ledge 67 operates merely the supplemental clamp 62.

If, however, the latches 70 are thrown over to their other extreme position, as shown in Fig. 5, they free the main clamp from the pin 54 and at the same time, by sliding beneath the projecting tongues 68 on the plate 62 lock the two clamping plates together as shown in Fig. 5. With the latches in this position the finger pressure on the ledge 67 will operate to raise the clamping bar 51 from the drum anvil 41 of the main clamp.

It is frequently desirable to skew the master sheet slightly after it is mounted on the drum to true up the image in case it is not strictly parallel with the side edges of the sheet, or in case the clamped end of the sheet is not absolutely at right angles to the sides. To provide for this, I mount in the arms 22 of the leading clamp a longitudinal rod 80 threaded in one of such arms and its ends abutting the inner surface of the end members of the drum. A suitable knurled collar 81 on this rod furnishes ready means for rotating it in either direction to shift the clamp correspondingly a short distance, if necessary for accurate presentation of the image.

The hooks 29 of the leading clamp and the hooks 51 of the main clamp at the trailing end may readily mount on the drum a sheet having a row of openings across its ends as indicated by the sheet B in Fig. 8. For some uses, however, it is desirable to employ a short supplemental master sheet overlying the sheet B. Such a supplemental sheet is shown at C in Fig. 8. It may readily have a length somewhat greater than the width of the sheet B and is so shown. This supplemental sheet has a pair of openings c through it adjacent its trailing end and my machine provides a pair of hooks adapted to be forced into position in the openings whenever desired to clamp the trailing end of such sheets. This mechanism will now be described with particular references to Figs. 1, 2 and 7.

I mount rotatably in the drum a shaft 90 rigidly carrying a pair of rock arms 91 formed with outward hooks 92. A spring 93 coiled about the shaft and anchored at one end to one of the arms and at the other end to the drum tends to swing the arm into the position shown in Fig. 2, where

they are entirely idle within the periphery of the drum and at the end of arcuate slots 95 in the drum which are occupied by the hooked arms. At the external end of the shaft 90 I provide a thumb segment 97 shown in Fig. 1 and indicated in broken lines in Fig. 2.

When the supplemental sheet C is hooked onto the hooks 29 of the leading end clamp the sheet extending around the drum will overlie all of the slots 95; then the operator by simple engagement of the thumb with the knurled segment 97 may swing the hooks so that they pass outwardly through the opening c in the surmounting sheet. Then a release of the thumb pressure on the segment 97 allows the spring 93 to swing the hooks into binding position where the hook members 92 overlie the face of the supplemental sheet C beyond the range of the member to coact therewith, be it a platen for direct printing or a blanket for offset printing.

I have referred to the short sheet C as a supplemental sheet surmounting another master sheet. It is to be borne in mind, however, as will be readily understood, that the sheet C may be used without the sheet B if there is occasion therefore. Furthermore, the sheet C may not be as short as shown in Fig. 8 but may extend beyond the openings c and still be effectively held in place by the hooks passing through such openings.

It will be seen that my clamping system is practically universal for all sorts and types of sheets to be fastened. The sheets may be of metal or of paper; they may have openings along their ends or such end portions may be imperforate. The projecting hooks provide ready means for engaging any sheet provided with properly spaced openings. If, however, the sheet has no openings and relies merely on a bending or kinking of the edge portion of the sheet, which may be very effective with light paper sheets, then the clamping means provides for that condition. Furthermore, the clamp for the non-perforate sheet may be readily thrown to idle position whenever desired so that the main clamp for the perforated sheets can be operated without regard to the supplemental clamp. Likewise when the supplemental clamp is used the main clamp is effectively held in idle position so as not to interfere with the action of the supplemental clamp.

Notwithstanding the independence of the two clamping actions, they are consolidated into one composite clamp by the novel characteristic of employing the clamping member of one clamp as the anvil for the other clamp. At the leading end the clamping member makes the anchorage for the perforate sheet. At the trailing end the clamping member for the perforated sheet forms the anvil for the clamp for the non-perforated sheet.

It should be noted also that the supplemental clamp for the short master sheet, shown as coacting with the sheet held by the main clamps, may be used with sheets held by the clamp for imperforate masters. If the sheet C is of metal it will ordinarily be formed with openings c through it. If it is of paper, the openings may be pre-formed or punched through the sheet by the projecting hooks themselves. That is to say, the hooks 92 may be turned out into a position beyond the periphery of the drum but not reaching the final position and then the sheet pressed onto such projecting hooks until the hooks pass through the sheet, after which the spring 93 will

swing the hooks into a position shown in Fig. 7 to clamp the sheet.

I claim:

1. The combination of a rotary drum having a ledge to form an anvil for a sheet, a pivoted clamping member mounted in the drum having an edge adapted to coact with the ledge to clamp a sheet between them, a sleeve threaded in the clamping member, a slideable rod mounted in the sleeve adapted to coact with the drum, and a camming arm carried by the sleeve and adapted to coact with the rod to force the clamping member into idle position with reference to a clamping ledge on the drum.
15. 2. The combination of a printing drum, means for clamping a master sheet thereon and for holding the leading edge of a supplemental master sheet over the first master sheet, said supplemental master sheet having openings through it adjacent its edges, said drum having a pair of hooks adapted to extend beyond the periphery of the drum and pass through said openings, and spring means acting on the hooks to lock the engaged portion of the supplemental master sheet to the drum.
20. 3. The combination of a rotary drum having a ledge to form an anvil, a pivoted clamping member mounted in the drum and having an edge adapted to coact with the ledge to clamp a sheet between them, a rod slidably mounted in the pivoted member and adapted to abut a stop on the drum, and a cam carried by the pivoted member and adapted to shove the rod axially toward the ledge and thereby move the clamping edge away from the anvil.
25. 4. The combination of a printing drum having a gap, a ledge carried by the drum within the gap, a pivoted member in the drum having a portion to coact with said ledge to clamp a sheet between them, a row of pins on the pivoted member projecting outwardly and also in a direction away from the adjacent edge of the gap to provide hooks adapted to form an anchorage for a sheet having a row of holes across its end, a spring tending to maintain said pivoted member seated against the ledge, and means for moving the pivoted member in opposition to the spring.
30. 5. The combination of a drum adapted to carry a master sheet, a clamp thereon for holding the leading end of said sheet, said clamp being adapted also to hold the leading end of a surmounting supplemental sheet wider than the main master sheet, and means on the drum adapted to engage such supplemental master sheet beyond the side edges of the main master sheet for retaining the free end of the supplemental sheet without obstructing the uncovered portion of the main master sheet.
35. 6. The combination of a drum having a gap, a pair of devices within the gap adapted respectively to hold the leading end and the trailing end of a master sheet, the holder for the leading end being formed to hold at the same time the end of a supplemental sheet which does not reach the trailing end holder, and means circumferentially between said two devices for engaging the side margins of such supplemental sheet in regions outside of the printing area thereof and thereby retaining the free end thereof.
40. 7. The combination of a drum having a gap, means within the gap for holding the leading ends of a main master sheet and a surmounting wider supplemental master sheet, and holding means carried by the drum adapted to engage

trailing portions of the supplemental sheet beyond the marginal edges of the main master sheet.

8. The combination of a drum having cylindrical surface with a gap, a pair of clamps within the gap adapted respectively to engage the leading end and the trailing end of a main master sheet embracing said cylindrical surface, and means carried by the drum circumferentially between said two clamps and adjacent the ends of the drum and adapted to extend radially beyond the cylindrical surface of the drum for engaging only a side margin of a shorter supplemental master sheet surmounting the main master sheet.

9. The combination of a drum having a cylindrical surface with a gap, means in the gap for clamping a master sheet and a surmounting supplemental master sheet across the leading ends of the sheets, and a retaining device movably mounted within the drum and adapted to extend through openings in the cylindrical surface of the drum and engage trailing portions of said supplemental master sheet adjacent the side margins only thereof.

10. The combination of a drum having a gap and a cylindrical surface adapted to support a main master sheet and a surmounting supplemental master sheet both in printing position,

5

10

15

20

25

means in the gap for clamping said sheets across their leading ends, a pair of hooks pivotally mounted within the drum, said hooks being adapted to lie entirely within the drum or to extend radially beyond its cylindrical surface through arcuate openings through said cylindrical surface of the drum adjacent its ends leaving the cylindrical surface uninterrupted between the arcuate openings, and spring means acting on the hooks and tending to swing them in a direction away from the clamping means for the leading end to apply tension to the supplemental sheet adjacent its trailing end.
